(57) **CLAIM**

The ornamental design for a fuel tank for a work vehicle, as shown and described.

DESCRIPTION

FIG. 1 is a top, rear, left perspective view of a fuel tank for a work vehicle embodying our new design;

FIG. 2 is a left perspective view thereof;

FIG. 3 is a right perspective view thereof;

FIG. 4 is a front perspective view thereof;

FIG. 5 is a rear perspective view thereof;

FIG. 6 is a top view thereof;

FIG. 7 is a bottom view thereof;

FIG. 8 is a top, rear, left perspective view thereof showing work vehicle environment;

FIG. 9 is a rear, left perspective view thereof showing work vehicle environment; and,

FIG. 10 is a top, rear, left perspective view thereof showing different unclaimed boundary.

The broken line representations in the figures show unclaimed environment or boundaries, and thus form no part of the claimed design.

The nature of this product is a fuel tank for a work vehicle, such as a tractor.
